UNITED STATES PATENT OFFICE.

DAVID NICKEL, OF MORRIS, ILLINOIS.

DESIGN FOR A CASING FOR DOOR-HANGER FRAMES.

SPECIFICATION forming part of Design No. 27,297, dated July 6, 1897.

Application filed May 17, 1897. Serial No. 636,997. Term of patent 7 years.

To all whom it may concern:

Be it known that I, DAVID NICKEL, a citizen of the United States of America, residing at Morris, in the county of Grundy and State 5 of Illinois, have invented and produced a new and original Design for an Outer Casing for Door-Hanger Frames, of which the following is a specification.

My invention relates to a certain new and 10 useful configuration for an outer casing for door-hangers.

The invention is illustrated by the drawing presented herewith, which shows the rear face of the outer casing in perspective.

15 The casing here shown consists of a lower pear-shaped portion A, extending upward into a circular portion A', the two portions being joined along an arc of the circular portion, so that the lower part of the circle is omitted. 20 Said circular portion is in the form of a cup having an outwardly-extending flange a,

around the margin of which is a flange a', substantially at right angles to the flange a.

The essential portion of my design I consider to be the cup-shaped portion A', having the 25 outwardly-extending flange a, provided with the marginal flange a', substantially at right angles to the flange a.

I claim as new and desire to secure by Letters Patent—

The design for an outer casing for door-hanger frames; substantially as shown and described.

In witness whereof I have hereunto set my hand, at Morris, in the county of Grundy and 35 State of Illinois, this 13th day of May, A. D. 1897.

DAVID NICKEL.
